UNITED STATES PATENT OFFICE

JOHN NIEJADLIK, OF GLENDALE, NEW YORK

WINDOW SASH LOCK

Application filed February 10, 1930, Serial No. 427,271. Renewed February 2, 1932.

This invention relates to window sash locks and has for one of its important objects to provide, in a manner as hereinafter set forth, a device of this character embodying a construction and arrangement of parts whereby both the upper and lower sashes of a window may be expeditiously secured simultaneously in any adjusted position.

Another important object of the invention is to provide a window sash lock including means for rigidly locking the upper and lower sashes together and further having means for locking or securing said lower sash to the window frame in which the same is slidably mounted.

Other objects of the invention are to provide a window sash lock of the character set forth which will be simple in construction, strong, durable, efficient in its use and which may be manufactured at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a perspective view showing a window sash lock constructed in accordance with this invention mounted on a window and in operative position.

Figure 2 is a view in front elevation of the invention.

Figure 3 is a top plan view partly broken away in horizontal section of the device.

Figure 4 is a rear end elevation thereof.

Referring to the drawings in detail, the reference character 1 designates the frame of the window in which the lower and upper sashes 2 and 3, respectively, are slidably mounted. The upper sash 3 is disposed between the parting strip 4 and the outer guide strip 5 and the lower sash 2 is mounted between the parting strip 4 and the inner guide strip 6. As usual, the sashes 2 and 3 are provided with the meeting rails 7 and 8 respectively at their adjacent ends.

Mounted on one end portion of the upper side of the meeting rail 7 of the sash 2 is a

horizontally disposed metallic bar 9 having a foot or base portion 10 disposed on the top of said meeting rail and provided with a transverse slot or recess 11 in its free edge for the reception of a securing screw 12 which is anchored in the meeting rail 7. The bar 9 is vertically disposed and is substantially flush with the inner vertical face of the meeting rail 7, as illustrated to advantage in Figures 1 and 3 of the drawings.

At its outer end, the bar 9 is provided with an upstanding enlargement 13 formed integrally thereon and having laterally projecting teeth 14 on its free marginal portion adapted to bite into the inner side of the guide strip 6, said enlargement 13 constituting one of a pair of jaws. The jaw 13 is provided, on the end thereof remote from the bar 9, with an integral right angularly disposed extension 15 which extends in opposed relation to the adjacent space of the frame 1.

A jaw 16 is shiftably mounted on the extension 15 of the jaws 13 through the medium of a right angularly disposed extension 17 which, as illustrated to advantage in Figure 4 of the drawings is provided with elongated slots 18 for the reception of the headed pins 19 which are mounted in said extension 15. The jaw 16 is provided with projecting teeth or lugs 20 adapted to bite into the adjacent side of the parting strip 4. The jaw 16 is further provided with an integral right angularly disposed extension 21 on its inner side upon which is eccentrically mounted a spur wheel 22 through the medium of the supporting screw or pin 23. The spur wheel 22 is adapted to bite into the adjacent face of the upper sash 3 when the jaw 16 is engaged with the parting strip 4 in a manner to securely lock the upper sash to the lower sash and at the same time lock said lower sash between the parting strip 4 and the inner guide strip 6.

An integral casing 24 extends inwardly from the extension 15 and encloses a pair of wedge blocks or cams 25 and 26 which are mounted on the jaws 13 and 16, respectively. A screw 27 is mounted for rotation through the forward wall of the casing 24 and is provided with a threaded shank 28 upon which

is mounted a wedge member 29 adapted for engagement with the cams 35 and 26 in a manner to cause the spreading of the jaws to locking position. On its outer end the screw 27 is provided with a winged head 30 to facilitate the operation of said screw.

When the screw is actuated in a manner to engage the wedge 29 with the cams 35 and 26, the teeth 14 and 20 on the jaws 13 and 16, 10 respectively, are caused to bite into the inner side strip 6 and the parting strip 4 and the lower sash 2 may thus be secured in any desired position in the window frame. As the inner jaw 16 moves into engagement with the 15 parting strip 4 the spur wheel 22 is engaged with the upper sash 3 and in this manner the upper sash is rigidly secured to the lower sash in any desired position relative thereto.

It is believed that the many advantages of 20 a window sash lock constructed in accordance with this invention will be readily understood, and although the preferred embodiment of the invention is as illustrated and described, it is to be understood that changes 25 in the details of construction may be had which will fall within the scope of the invention as claimed.

What is claimed is:—

1. A window sash lock of the character described comprising a pair of complementary 30 jaws slidably connected together and adapted for disposition between the parting strip and a guide strip of a window frame, a casing formed on one of said jaws, cams formed on 35 said jaws and disposed within the casing in spaced opposed relation to each other, a screw rotatably mounted in the casing and extending between the cams and a wedge threadedly mounted on the screw for actuation thereby, 40 said wedge engageable with the cams in a manner to shift the jaws to locking and unlocking positions.

2. A window sash lock of the character described comprising a pair of complementary 45 jaws slidably connected together and adapted for disposition between the parting strip and a guide strip of a window frame, a casing formed on one of said jaws, cams formed on 50 said jaws and disposed within the casing in spaced opposed relation to each other, a screw rotatably mounted in the casing and extending between the cams and a wedge threadedly mounted on the screw for actuation thereby, 55 said wedge engageable with the cams in a manner to shift the jaws to locking and unlocking positions, an integral extension on one of the jaws, and a spur wheel eccentrically mounted on the extension and engageable with another sash of the window for 60 locking said other sash to the first named sash.

In testimony whereof I affix my signature.

JOHN NIEJADLIK.
